DAWSON M. TAGGART, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,312,768.

Specification of Letters Patent.

Patented Aug. 12, 1919.

Application filed November 17, 1917. Serial No. 202,515.

To all whom it may concern:

Be it known that I, DAWSON M. TAGGART, a citizen of the United States, residing at East Orange, in the county of Essex and 5 State of New Jersey, have invented certain new and useful Improvements in Telephone-Exchange Systems, of which the following is a full, clear, concise, and exact description.

This invention relates to telephone exchange systems, and more particularly to such systems as the central energy type.

The object of the invention is to provide improved signaling means for such systems.

In accordance with the feature of this invention, apparatus associated with a link circuit connected with a telephone line functions upon the opening and subsequent closure of the telephone line to cause the intermittent operation of a signaling device 20 which is common to a plurality of link circuits, thereby to furnish a recall signal to a central office operator. The subsequent actuation of a switch common to the plurality of link circuits causes the operation of a signaling device individual to the engaged link circuit, whereby the particular line upon which the recall has been made is identified.

For a more complete understanding of this invention, reference should be had to 30 the following description considered in connection with the accompanying drawing illustrating one embodiment of this invention, and wherein there are shown two telephone lines A and B which may be connected through a link circuit C. It is to be understood that many lines similar to A and B may terminate at the same central office and that a plurality of link circuits similar to C may be employed for interconnecting such lines. The apparatus shown 40 within the dotted rectangle 5 is common to a plurality of link circuits. It is thought that the nature of this invention is such that a complete understanding thereof may 45 be had from a description of the operation of the system disclosed in the drawing, and it will be so described.

Subscriber A, in initiating a call, removes the receiver from the switchhook, thereby 50 causing the lighting of line lamp 6 in the usual manner. The operator, upon observing the lighted condition of the line lamp 6, inserts answering plug 7 of cord circuit C into line jack 8, whereupon cutoff relay 9 55 and supervisory relay 10 operate. Answer-

ing supervisory lamp 11 is not lighted at this time for the reason that a low resistance shunt, including a resistance coil 12 and the left-hand winding of relay 13 is established therefor by the operation of the supervisory relay 10. The left-hand winding of relay 13 is of low resistance, while its right-hand winding is of high resistance, the purpose of which will more fully hereinafter appear. The establishment of this shunt circuit about the lamp 11 causes the operation of the relay 13 over a circuit from battery through the contact of switch 14, left-hand winding of relay 13, right-hand normal contact of relay 15, contact of supervisory relay 10, left-hand normal contact of relay 15, resistance coils 12 and 16, sleeve contacts of the answering plug 7 and jack 8, and the winding of the cutoff relay 9 to ground. The operation of 65 relay 13 connects an interrupter 17 in circuit with a pilot lamp 18, thereby causing the intermittent operation thereof. This pilot lamp 18 is common to a plurality of link circuits. The intermittent operation of 70 this pilot lamp is an indication to the operator that some action upon her part is required in establishing a connection.

The operator thereupon actuates listening key 20, causing the operation of relay 15, over 75 a circuit from battery through the right-hand winding thereof and the contact of listening key 20 to ground. Relay 15, in operating, establishes a locking circuit for itself from battery through the right-hand alternate contact thereof, contact of supervisory relay 10, left-hand alternate contact of relay 15, resistance coil 16, sleeve contacts of the answering plug 7 and jack 8, and the winding of cutoff relay 9 to ground. The operation 80 of relay 15 opens the hereinbefore-mentioned shunt circuit, which includes the low resistance winding of relay 13, and substitutes therefor another shunt circuit including the left-hand winding of the relay 15, 85 which is in the locking circuit of relay 15. The left-hand winding of relay 15 is of low resistance to prevent the lighting of the answering supervisory lamp 11. The opening 90 of the first-mentioned shunt circuit releases 105 the common relay 13, whereupon the pilot lamp 18 is extinguished.

The operator, upon being advised that the connection is desired with the line of subscriber B, restores the listening key 20 to 110

normal position and inserts calling plug 21 in line jack 22, whereupon calling supervisory lamp 23 is lighted and cutoff relay 24 operated. Subscriber B may be signaled by the operation of the usual ringing key 25 and, upon responding to the operation of the call bell, the removal of the receiver from the switchhook causes the operation of calling supervisory relay 30. Upon the 10 operation of this supervisory relay 30, a shunt circuit, including resistance coil 31, is established for and extinguishes the lamp 23.

Upon the conclusion of the conversation, the subscribers restore the receivers to the 15 switchhooks, whereupon the answering and calling supervisory relays 10 and 30 are de-energized to open the shunt circuits about the answering and calling lamps 11 and 23, whereupon these lamps are lighted to furnish 20 disconnect signals. The deenergization of the answering supervisory relay 10 also opens the locking circuit for the relay 15, which thereupon releases its armatures. If, before the plugs are withdrawn from the 25 jacks, the calling subscriber A desires to initiate another call, the mere removal of the receiver from the switchhook causes the intermittent operation of the pilot lamp 18, due to the operation of the common relay 13 upon the energization of the answering 30 supervisory relay 10. The operation of the supervisory relay 10, in closing the energizing circuit through the left-hand low resistance winding of the common relay 13, also 35 thereby establishes the low resistance shunt circuit including the resistance 12, whereupon the answering supervisory lamp 11 is extinguished. The operator, then, upon observing the flashing of the pilot lamp 18, 40 may actuate the common switch 14, thereby opening the contact thereof and removing a short circuit of the high resistance right-hand winding of relay 13. This high resistance winding is then included in the 45 shunt circuit about the lamp 11, thereby making this shunt circuit of such high resistance that the lamp 11 will be lighted. In this manner, the operator may definitely determine which of several engaged cord 50 circuits is connected with the line which has initiated a recall. The key 14 may now be restored to normal position, and the listening key 20 actuated to connect the operator with the line upon which the recall has been 55 made. If another connection is desired, this may be completed in the usual manner.

When both supervisory lamps are lighted a disconnect signal is furnished the operator, who may thereupon withdraw the plug 60 from the jacks and restore all apparatus to normal condition.

What is claimed is:

1. A telephone exchange system comprising telephone lines, a plurality of link circuits for interconnecting the lines, one of

which is connected with one of the lines, a supervisory relay and a signaling device in the engaged link circuit, a signal device common to the link circuits, means controlled by the supervisory relay and rendered effective upon the opening and subsequent closure of the engaged line to cause the operation of the common signaling device, a normally ineffective energizing circuit for the signaling device individual to the engaged link circuit, and a switch actuated subsequent to the operation of the common signaling device for rendering the energizing circuit effective for energizing the individual signaling device. 70 75 80

2. A telephone exchange system comprising telephone lines, a plurality of link circuits for interconnecting the lines, one of which is connected with one of the lines, a supervisory relay and a signaling device in the engaged link circuit, a signaling device common to the link circuits, a relay responsive to the opening of the telephone line, a relay responsive to the subsequent closure of the telephone line and cooperating with the second-mentioned relay to cause the intermittent operation of the signaling device when the supervisory relay is energized, a normally ineffective energizing circuit for the signaling device individual to the engaged link circuit, and a switch actuated subsequent to the operation of the common signaling device for rendering the energizing circuit effective for energizing the individual signaling device. 90 95 100

3. A telephone exchange system comprising telephone lines, a plurality of link circuits for interconnecting the lines, one of which is connected with one of the lines, a supervisory relay and a signaling device in the engaged link circuit, a signaling device common to the link circuits, a relay individual to the engaged link circuit responsive to the opening of the telephone line, a relay common to a plurality of link circuits responsive to the subsequent closure of the telephone line and cooperating with the individual relay to cause the intermittent operation of the common signaling device while the supervisory relay is energized, a normally ineffective energizing circuit for the signaling device individual to the engaged link circuit, and a switch actuated subsequent to the operation of the common signaling device for rendering the operating circuit effective for energizing the individual signaling device. 105 110 115 120

4. A telephone exchange system comprising telephone lines, a plurality of link circuits for interconnecting the lines, one of which is connected with one of the lines, a supervisory relay and a signaling device in the engaged link circuit, an operator's telephone set, a listening key for connecting the operator's telephone set to the engaged link 125 130

- circuit, a relay individual to the engaged link circuit energized upon the actuation of the listening key, a locking circuit for the individual relay established upon the energization thereof and including a contact of the supervisory relay, a signaling device common to the link circuits, a relay common to the link circuits energized upon the de-energization of both the supervisory and individual relays followed by the energization of the supervisory relay, and interrupter mechanism brought into circuit with the common signaling device by the energization of the common relay.
- 5 5. A telephone exchange system comprising telephone lines, a plurality of link circuits for interconnecting the lines, one of which is connected with one of the lines, a supervisory relay controlled over the engaged telephone line, a supervisory lamp in the engaged link circuit, a signaling device common to the link circuits, means controlled by the supervisory relay and rendered effective upon the opening and subsequent closure of the engaged line to cause the operation of the common signaling device, and a switch subsequently actuated to cause the lighting of the supervisory lamp.
- 10 6. A telephone exchange system comprising telephone lines, a plurality of link circuits for interconnecting the lines, one of which is connected with one of the lines, a supervisory relay controlled over the engaged link circuit, a lamp common to the link circuits, a relay individual to the en-
- 15 gaged link circuit responsive to the deenergization of the supervisory relay when the engaged line is open, a relay common to the link circuits responsive to the subsequent energization of the supervisory relay upon the closure of the engaged line and coöperating with the individual relay to cause the lighting of the common lamp, and a switch subsequently actuated to cause the lighting of the supervisory lamp.
- 20 7. A telephone exchange system comprising telephone lines, a plurality of link circuits for interconnecting the lines, one of which is connected with one of the lines, a supervisory relay and a signaling device in the engaged link circuit, a normally ineffective energizing circuit for the signaling device rendered effective by the deenergization of the supervisory relay and ineffective by the energization thereof, a signaling device common to the link circuits, a relay individual to the engaged link circuit responsive to the deenergization of the supervisory relay, a relay common to the link circuits responsive to the subsequent energization of the supervisory relay and coöperating with the individual relay to cause the operation of the common signaling device, and a switch subsequently actuated to render the energizing circuit of the individual signaling device effective while the supervisory relay is energized.
- 25 8. In witness whereof, I hereunto subscribe my name this 14th day of November A. D., 1917.
- 30 DAWSON M. TAGGART.
